UNITED STATES PATENT OFFICE.

WILLARD T. SEARS, OF BROOKLYN, NEW YORK, ASSIGNOR TO NILES-BEMENT-POND COMPANY, OF NEW YORK, N. Y., A CORPORATION OF NEW JERSEY.

ADJUSTING MECHANISM FOR DRILLING-MACHINES.

1,296,863.

Specification of Letters Patent. Patented Mar. 11, 1913.

Application filed April 22, 1913. Serial No. 229,993.

To all whom it may concern:

Be it known that I, WILLARD T. SEARS, a citizen of the United States, residing at Brooklyn, in the county of Kings and State of New York, have invented certain new and useful Improvements in Adjusting Mechanisms for Drilling-Machines, of which the following is a specification.

The invention is particularly applicable to a radial drilling machine and will be described in connection with such a machine; but it will be understood that the invention, as concerns some of its features, may be used in connection with other drilling machines or even in connection with machines for other purposes. As applied to a radial drill and as illustrated in the drawing, the adjusting mechanism is used for raising or lowering the drill arm together with the parts immediately associated therewith. The adjusting mechanism is similar in some respects to that shown and described in my patent for adjusting mechanism No 1,122,649 dated December 29th, 1914.

The object of the present invention is to provide an adjusting mechanism of this type having improved structural features and improved arrangement of parts whereby certain important advantages are secured. In accordance with one feature of the invention I arrange and position the frictional connection in a novel way, it preferably being interposed between the screw and the main frame and being located at a position where it is readily accessible and where it can be easily lubricated.

In the accompanying drawing which shows the preferred embodiment of the invention as applied to a radial drilling machine:

Figure 1 is an elevational view of a drilling machine.

Fig. 2 is a vertical sectional view, on an enlarged scale, taken along the line 2—2 of Fig. 1.

Fig. 3 is a fragmentary sectional view taken along the line 3—3 of Fig. 2.

Fig. 4 is an enlarged detail view showing the elevating screw and the parts immediately associated therewith.

Referring to the drawing, 1 represents the base, 2 the column and 3 the vertically adjustable arm of a radial drilling machine.

In the preferred embodiment of the invention, as illustrated, the column is divided,

as shown in my Patent 1,071,590, dated August 26th, 1913. The arm 3 or a carrying member therefor extends between the two parts of the column and is suitably guided thereon for vertical movement. Rigidly mounted at the rear end of the arm is a gear casing 4 which carries an electric motor 5. Slidably mounted on the arm 3 is a saddle 6 carrying a head provided with a rotatable drill spindle 7. A driving shaft 8 extends longitudinally of the arm and serves to drive the spindle.

Mounted on the shaft of the motor 5 is a pinion 9 which meshes with a gear 10 loosely mounted on the shaft 8. Connected with the gear 10 is a pinion 11 which meshes with a gear 12 on a countershaft 13. Mounted on the shaft 13 is a pinion 14 which is adapted to mesh with a gear 15 splined on the shaft 8 and movable by means of a hand lever 16. With the parts in the position shown in Fig. 1, the shaft 8 is driven at a relatively low speed indirectly from the motor through the countershaft 13. When the gear 15 is moved toward the left it is disengaged from the pinion 14 and is engaged with clutch teeth at the end of the pinion 11, thus making a direct high speed drive from the gear 10 to the shaft 8. It will be understood that the entire gear mechanism, as described, is mounted within the casing 4 and that this casing, with the gearing and with the motor 5, is vertically movable with the arm 3.

For adjusting the arm and connected parts vertically, there is provided a vertical screw 17 and a nut 18 and means for rotating one of them relatively to the other. Preferably the screw is normally fixed against rotation and the nut is turned, preferably by power derived from the motor 5. As illustrated, the nut 18 is fitted in a bearing 19 secured to the arm 3. The screw 17 is suitably supported in a manner to be described and the nut 18 serves to support the entire weight of the arm and the associated parts upon the screw. Preferably a ball bearing 20 is interposed between the arm and the nut, that is, between the bearing 19 and the nut. A collar 20^a prevents downward movement of the nut with respect to the bearing. Secured to or formed integrally with the nut 18 is a bevel gear 21 which meshes with a bevel gear 22. The gear 22 is carried by a shaft 23 in alignment with the aforesaid 110

shaft 13. A jaw clutch element 24 is secured to the shaft 23 and a companion grooved jaw clutch element 25 is splined to the shaft 13. For shifting the clutch element 25 there is provided a rock shaft 26 carrying a forked lever 27 projecting into the groove of the clutch element 25. The rock shaft 26 carries a handle 28 by means of which the clutch may be operated.

10 Assuming the motor to be in operation, and the clutch elements 25 and 24 to be engaged, it will be seen that rotative movement will be transmitted from the shaft 13 through the bevel gears 22 and 21 to 15 the nut 18. The motor can be rotated in either direction under the control of a controller, not shown, and thus the nut 18 can be rotated in either direction. As the nut rotates it moves upward or downward along 20 the screw 17, carrying the arm 3 and the associated parts with it.

I have stated that the screw 17 is normally fixed against rotation; but in accordance with the invention I provide means 25 whereby the screw may turn when necessary to protect the machine from injury. As illustrated, the screw is supported at the top of the column by a frictional device. A plate 29 is secured to the top of the screw, 30 this having a conical flange 30 which projects into and fits a conical seat 31 in a plate 32 secured to the top of the column. During normal operation the friction resistance between the flange 30 and the seat 31 will 35 prevent the screw 17 from turning.

Means is provided whereby the upward movement of the nut along the screw is positively stopped without any jamming of the threads. As illustrated, the thread on 40 the screw terminates at the top abruptly with a shoulder, as indicated at 33 in Fig. 4, and the nut is shaped so that the thread presents a squared end as indicated at 34, this squared end 34 being adapted to abut 45 the shoulder 33. It will be seen that if the operator permits the upward movement of the nut to continue, the squared end 34 will engage the shoulder 33 which serves as a stop to limit relative movement of the nut. 50 Thereafter the rotative force applied to the nut 10 will rotate the screw 17 against the frictional resistance offered at 30 and 31. This rotative movement of the screw 17 will continue indefinitely, thus preventing any 55 injury to the machine which would otherwise result.

The operator, through inadvertence or carelessness, may permit the nut to turn in the other direction so as to move the arm 3 60 downward too far. The arm on its downward movement may meet some obstruction, such for instance as a piece of work about to be drilled; or it may move downward until it reaches the bottom of the column.

65 In either case the weight of the arm will

be removed from the screw and carried by the obstruction or by the bottom of the column. When the screw is thus relieved from weight, the frictional contact at 30 and 31 is reduced because of the decreased pressure and thus the screw 17 is permitted to turn freely with the nut. This rotative movement of the screw will continue indefinitely without injury to the machine which would otherwise result.

70 It will be seen that the plate 32 is adapted to serve as a reservoir for lubricant, thus keeping the bearing surfaces at 30 and 31 thoroughly lubricated. An oil hole such as indicated at 35 may be provided for supplying lubricant to the reservoir.

75 What I claim is:

1. In a drilling machine comprising a vertical column and an arm vertically adjustable thereon, the combination with the arm, 80 of a supporting and adjusting means therefor comprising a vertical screw and a nut, power means for turning one of them relatively to the other to raise or lower the arm, and a frictional device normally holding the 85 other of them against rotation but permitting it to turn when the arm is prevented from moving.

2. In a drilling machine comprising a vertical column and an arm vertically adjustable 90 thereon, the combination with the arm, of a supporting and adjusting means therefor comprising a vertical screw and a nut, power means for turning one of them relatively to the other to raise or lower the arm, a stop 95 for positively stopping the relative turning movement in one direction, and a frictional device normally holding the other of them against rotation but permitting it to turn when the relative turning movement is 100 stopped.

3. In a drilling machine comprising a vertical column and an arm vertically adjustable thereon, the combination of a vertical screw, a nut engaging the screw and serving 110 to support the arm, power means for turning the nut to raise or lower the arm, and a frictional device normally holding the screw against rotation but permitting it to turn with the nut when the arm is prevented from 115 moving.

4. In a drilling machine comprising a vertical column and an arm vertically adjustable thereon, the combination of a vertical screw, a nut engaging the screw and serving 120 to support the arm, power means for turning the nut to raise or lower the arm, a stop for positively stopping the movement of the nut on the screw in one direction, and a frictional device normally holding the screw 125 against rotation but permitting it to turn with the nut when the relative movement of the nut is stopped.

5. In a drilling machine comprising a vertical column and an arm vertically adjust- 130

able thereon, the combination of a vertical screw, a nut engaging the screw and serving to support the arm, power means for turning the nut to raise or lower the arm, and a frictional device at the top of the column normally holding the screw against rotation but permitting it to turn with the nut when the arm is prevented from moving.

6. In a drilling machine comprising a vertical column and an arm vertically adjustable thereon, the combination of a vertical screw, a nut engaging the screw and serving to support the arm, power means for turning the nut to raise or lower the arm, and a frictional device engaging the screw and serving to support it and the parts carried thereby, the said friction device normally holding the screw against rotation but permitting it to turn with the nut when the arm is prevented from moving.

7. In a drilling machine comprising a vertical column and an arm vertically adjustable thereon, the combination of a vertical screw, a nut engaging the screw and serving to support the arm, power means for turning the nut to raise or lower the arm, and a frictional device at the top of the column engaging the screw and serving to support it and the parts carried thereby, the said friction device normally holding the screw against rotation but permitting it to turn with the nut when the arm is prevented from moving.

8. In a drilling machine comprising a vertical column and an arm vertically adjustable thereon, the combination of a vertical screw, a nut engaging the screw and serving to support the arm, power means for turning the nut to raise or lower the arm, and a frictional device supporting the screw and the parts carried thereby and normally holding the screw against rotation but permitting it to turn with the nut when the arm is prevented from moving, the frictional device being of the cone type and having one element secured to the screw and the other element carried by the column.

9. In a drilling machine comprising a vertical column and an arm vertically adjustable thereon, the combination of a vertical screw, a nut engaging the screw and serving to support the arm, power means for turning the nut to raise or lower the arm, and a frictional device supporting the screw and the parts carried thereby and normally holding the screw against rotation but permitting it to turn with the nut when the arm is prevented from moving, the frictional device being of the cone type and having one element secured to the screw and the other element carried by the column, the last said element being shaped to retain lubricant.

In testimony whereof I hereto affix my signature.

WILLARD T. SEARS.
